HEATER GRILL

Roy W. Hanson, 221 Yorktown, Dallas, Tex.

Filed Mar. 4, 1963, Ser. No. 73,798

Term of patent 14 years

(Cl. D81—21)

FIG. I

FIG. III

FIG. II

FIG. IV

FIG. V

FIG. I is a front perspective view of a heater grill showing my new design;

FIG. II is a front elevational view thereof;

FIG. III is a rear elevational view thereof;

FIG. IV is a side elevational view thereof; and

FIG. V is a top plan view.

I claim:

The ornamental design for a heater grill, substantially as shown.
